UNITED STATES PATENT OFFICE.

GEORGE B. PUTNAM, OF BOSTON, MASSACHUSETTS.

COMBINED CANE AND CAMP-STOOL.

SPECIFICATION forming part of Letters Patent No. 413,962, dated October 29, 1889.

Application filed November 24, 1888. Serial No. 291,784. (No model.)

To all whom it may concern:

Be it known that I, GEORGE B. PUTNAM, of Boston, in the county of Suffolk and State of Massachusetts, have invented certain new and useful Improvements in a Combined Cane and Camp-Stool, of which the following is a specification.

This invention has for its object to provide a folding stool which can be used as a cane at the convenience of the owner; and it consists in the improvements which I will now proceed to describe.

Of the accompanying drawings, forming a part of this specification, Figure 1 represents a side view of my improved device arranged as a walking-cane. Fig. 2 represents a perspective view of the same arranged as a seat. Fig. 3 represents a section on line *x x*, Fig. 1. Fig. 4 represents a section on line *y y*, Fig. 1.

Fig. 5 is a bottom plan view of the seat.

The same letters of reference indicate the same parts in all the figures.

In carrying out my invention I provide three rods 2 2 2, preferably of steel tubing, of suitable strength to support a person when in use as a seat, and of such diameter as that they may be inserted at their upper ends into a cylindrical portion *a*, which constitutes the handle of the cane. The bottom ends of the rods are secured by a ferrule *b*, adapted to be removed when necessary to form a seat.

The cane is formed into a seat by removing the upper portion *a* and sliding a loose ring *c* down on the rods a sufficient distance to allow the top and bottom of the same to open and assume the position represented in Fig. 2. I then place over the upper ends of the rods a seat *d*, preferably of duck or other suitable material, said seat being provided with pockets 3 3 3 at each of its corners, adapted to receive the ends of the rods and hold them in position, as shown in the above-mentioned figures. Any other suitable means may be provided to engage the seat with the rods.

It will be seen by reference to Fig. 2 that ring *c* forms an effective device for retaining

the rods in position to form a seat, and when the seat *d* is in position it forms a convenient stool. The rods being hollow, render the device of sufficient lightness to be convenient as a walking-cane.

When using the device as a cane, I prefer to attach the ring *c* to the upper portion *a* by a screw-thread, or in any other suitable way, so as to prevent said ring from being lost.

The device is easily and quickly changed from a cane to a seat, as the ferrule *b* and case *a* are fitted to be readily removed from the rods. The case *a* may be of sufficient length to entirely cover the rods 2. The upper portion of said case may be of sufficient size to permit the seat *d* to be inserted in it when compactly folded or rolled.

It is obvious that more than three rods may be employed.

I claim—

1. A seat-support composed of a plurality of rods 2 and a loose ring *c*, adapted to slide on said rods and to connect the central portions thereof, as set forth.

2. A stool composed of the independent rods 2, the loose ring thereon, and a detachable seat engageable with the upper ends of said rods, as set forth.

3. The flexible seat *d*, having pockets 3, combined with the rods 2, formed to engage said pockets, and the loose connecting-ring on said rods, as set forth.

4. The herein-described folding camp-stool, comprising the plurality of rods, the ring loosely secured thereon, the canvas seat having corner pockets, the ferrule, and the handle to which said ring is designed to be secured, substantially as set forth.

In testimony whereof I have signed my name to this specification, in the presence of two subscribing witnesses, this 21st day of November, A. D. 1888.

GEORGE B. PUTNAM.
